UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

POWER-DRIVE FOR ADDING-MACHINES.

1,054,628.

Specification of Letters Patent.

Patented Feb. 25, 1913.

Original application filed August 13, 1906, Serial No. 330,466. Divided and this application filed January 13, 1911. Serial No. 602,423.

To all whom it may concern:

Be it known that I, JESSE G. VINCENT, a citizen of the United States, residing at Detroit, in the county of Wayne and State of Michigan, have invented certain new and useful Improvements in Power-Drives for Adding-Machines, of which the following is a specification.

This application is a division of my prior application filed August 13, 1906, Serial No. 330,466. Here, as there, the power drive takes the form of an electric motor which during use of the adding machine runs continuously and is adapted to be connected to and disconnected from the adding machine by a spring-closed clutch under control of manual and automatic detent devices, the manual equipment enabling the user of the machine to operatively connect the motor thereto at will and the automatic detent equipment insuring the proper timing of cycles of operation. It is desirable that the connection be not effected between the drive and the machine unless the power has already been turned on and the motor is running, for otherwise the motor would have to pick up the load before gaining any headway.

The aim of the present invention is to prevent the user of the machine from effecting an operative connection between the drive and the machine, as by operating the manually controlled detent devices, unless the power is already on. The present embodiment of my invention being one which pertains to the use of an electric motor, I here arrive at the result by putting the starting connections or detent devices under control of the switch for turning on and off the electric current.

In the drawings which accompany and form part of this specification, Figure 1 is a partial side elevation of an adding machine with electric drive and an equipment for carrying out the present invention, some of the parts appearing in section. Fig. 2 is a detached view of the electric switch with the stem of the turn button in section and in the opposite position to that shown in Fig. 1, this view also including a portion of the detent connections. Fig. 3 is a vertical transverse section taken substantially on the line 3-3 of Fig. 1.

It will be unnecessary to describe in any

detail the adding machine itself. The type 55 of machine here indicated is the familiar Burroughs machine such as disclosed in numerous prior patents, of which it will suffice to mention Number 858,548, issued July 2, 1907, on an invention of mine which also related to the application of an electric drive to this type of adding machine. The reference numeral 300 designates the oscillating handle shaft of such a machine, which shaft carries the usual full stroke sector 311 connected by a link 366 to a crank arm 110 on another oscillating shaft 100 journaled in the rear of the base of the machine. Reference numeral 180 designates one of the usual operating springs which connects said crank 70 arm to the base of the machine, and the reference numeral 380 designates a power transmitting spring connecting said crank arm to a third oscillating shaft 800, which is also a familiar element of the Burroughs 75 adding machine. For operating the machine by hand a handle of the usual character is applied to the shaft 300. For operating by power in the present form of drive, connections are not made directly to the 80 shaft 300 as in the construction of my said prior Patent No. 858,548, but to the shaft 100 the same as shown in my original application No. 330,466, and also in my prior application No. 329,386. These connections 85 comprise a crank arm 2 secured to said shaft 100, an adjustable pitman 3, one member of which is coupled to said crank arm 2, and a radius link 4 coupled to the other member of said pitman and pivoted to the gear casing 90 5 of the drive equipment. The numeral 6 designates the driven shaft of this equipment, which shaft carries a snail-back cam 7 operating against a roller 8 carried by the pitman 3.

The shaft 6 has secured to it a clutch disk 9 recessed on its periphery for clutching purposes as shown at 10 in Fig. 1 and embraced by a clutch ring 11 which is secured to a worm wheel 12 loose upon the shaft 6. 100 see Fig. 3. The worm 13 meshes with said wheel and is fixed to a shaft 14, the latter uniting with the armature shaft of the electric motor 15. A driving connection between the ring 11 and disk 10 is effected 105 through the medium of clutch blocks 16, one of which is shown in Fig. 1 occupying recess 10 of the disk. A circular plate or

disk 17 which is loose upon a collar of the shaft 6 (Fig. 3) carries pins or studs, one of which appears in section of Fig. 1, being designated 18 and loosely engaging an opening 5 through the clutch block 16. A spring 19 tends to thrust said block in a direction to make it effective for establishing a driving connection between the ring 11 and disk 9, but normally the spring is restrained by 10 reason of restraint imposed upon the circular plate or disk 17. Thus the latter carries a segmental stop block 20 shown in dotted line in Fig. 1, which block normally abuts a pair of detent pieces 21 and 22 15 formed as heads upon arbors or short shafts 21^a and 22^a (Fig. 3), the engaging portions of said heads being semi-circular as indicated by dotted lines in Fig. 1. On the outer end of shaft 21^a there is secured a 20 gear segment 21^b and secured to the corresponding end of the shaft 22^a is a similar and intermeshing gear segment 22^b forming part of a bell crank lever. A forwardly extending arm 22^c of the latter is coupled to 25 the lower end of a bar 23, the latter extending up past the handle shaft 300 and to a point under that portion of the casing of the adding machine which constitutes the right hand side-bar 24 of the key-board 30 panel. The upper end of this vertical bar 23 is longitudinally slotted to receive a stud 25 on the rear end of a lever 26 which is connected by a spring 27 to the lower portion of 35 said vertical bar as shown in Fig. 1. Said lever 26 is mounted on a fixed pivot 26^a under the above mentioned portion of the machine casing and a second lever 27 mounted upon a similar pivot 27^a has a forked arm extending forward of said pivot and embracing a stud 26^b on the lever 26. Upwardly extending branches of said levers 26 and 27 are connected by a spring 28 which normally depresses the rear arm of the lever 26 so that the vertical bar 23 is held down 40 and consequently the detents 21 and 22 both engage the stop block 20 and the clutch remains open.

Reference numeral 30 designates a starting or drive controlling bar which extends 50 along the right hand side of the keyboard and has legs 31 passing loosely through slots in the panel bar 24 and being additionally guided for up and down movement by pins or studs 32 which pass through slots in said 55 legs as shown in Fig. 1. The lower ends of these legs are bifurcated to straddle studs at the ends respectively of the forwardly extending arm of the lever 26 and the rearwardly extending arm of the lever 27.

60 Obviously depression of the bar 30 will elevate the rearwardly extending arm of the lever 26 and through the medium of the spring 27 lift the vertical bar 23 and rock the detents 21 and 22 to disengage 65 them from the stop block 20, whereupon the

spring 19 thrusts the clutch piece 16 into effective engagement with the clutch ring 11 and clutch disk 9, and if the motor is running the shaft 6 will be rotated and the adding machine put through an operation. 70

Coming now to equipment for embodying the present invention, reference numeral 40 designates in general an "on and off" electric switch of any suitable type, the numeral 41 designating the turn button thereof 75 which, as is customary, requires a quarter of a rotation to change the switch from "off" to "on," and vice versa. For the purposes of the present invention a portion of the stem of said turn button is made oblong or rectangular in cross section as illustrated by dotted lines in Fig. 1 and in cross section in Fig. 2. This portion 42 of said stem occupies a key-hole slot in a link 43 which at its forward end is coupled to a 80 downwardly extending branch 22^d of the aforesaid detent bell crank. The said key-hole slot comprises a circular portion 43^a in which the turn button stem 42 may rotate and said slot also comprises narrow portions 43^b and 43^c of substantially the same lateral dimension as the smaller cross-sectional dimension of said turn button stem. 85

When the adding machine is at normal 90 the link 43 occupies a rearward position with the circular portion 43^a of its key-hole slot around the turn button stem 42, and if the current is off the rectangular portion of this stem stands crosswise of the link as indicated by dotted lines in Fig. 1 so 95 that it locks the link against lengthwise movement and therefore obviously prevents disengagement of the detents 21 and 22 from the stop block 20 and so prevents closing of the clutch. However, when the current is 100 turned on the rectangular portion of the turn button stem alines with the narrow portions of the key-hole slot, as shown in Fig. 2, so that it no longer locks the link 43 and the obstruction to the closing of the clutch 105 is removed. Thus it will be seen that the above stated object of the invention is effectively obtained, though it is of course to be understood that the invention is not necessarily limited to this particular form of 110 embodiment.

Means for properly timing the cycles of 115 operation of the adding machine, though forming no part of the present invention, may be briefly pointed out. A forwardly 120 and upwardly extending branch 23^a of the vertical bar 23 confronts a roller stud 311^a of the sector 311, so that as soon as the machine gets under way the bar 23 will be forcibly returned to its normal position, 125 rocking the detents 21 and 22 again into the path of the stop block 20. The other branch of said starting bar which appears as a short finger or lug 23^b is for the purpose of preventing an application of the handle to the 130

shaft 300 when the detents are displaced and, vice versa, for preventing displacing of the detents when the handle is rotatively engaged with said shaft 300.

5. The numeral 265 designates the familiar total key of the Burroughs adding machine, which key surmounts the usual bell crank lever 227, the latter being secured to a rock shaft from the right hand end of which 10 depends an arm 227^a. This arm is connected by a link 140 to a crank arm 141 on a rock shaft 142 which carries an arm 143 having a segmental outer end or head 144 lying adjacent the forwardly extending arm 15 of the aforesaid lever 126. The latter has a lock block 26^c which, when the starting bar 30 is depressed and the total key is at normal, passes down along the rear end of the head 144 to prevent an operation of the 20 total key while the starting bar is so depressed. Vice versa, if the total key is first depressed the head 144 moves under the lock block 26^c and prevents operation of the starting bar 30 until the total key is fully 25 depressed, when the forward end of the head 144 will have passed to the rear of said lock block.

What I claim is:

1. The combination with the prime mover 30 of the machine proper; of a power drive having means for turning on and off the motive force, and means for operatively connecting the drive with said prime mover at will with provisions for preventing such 35 connection when the motive force is turned off.

2. The combination with the prime mover of the machine proper; of an electric drive 40 having a switch for turning on and off the current, and means controlled by said switch for operatively connecting the drive with said prime mover.

3. The combination with the prime mover 45 of the machine proper; of a power drive applied thereto with an intervening clutch; and means for closing the latter with provisions for preventing such closing when

the motive force is turned off the power drive.

4. The combination with the prime mover 50 of the machine proper; of a power drive applied thereto with an intervening clutch and clutch closer, a detent for normally restraining the latter, and means preventing displacement of said detent when the motive force is turned off the power drive. 55

5. The combination with the prime mover of the machine proper, of an electric motor applied thereto with an intervening clutch and clutch closer, a rocking detent restraining 60 the latter, an on-and-off switch for the motor having a turn button with an oblong shank portion, and a link key-hole slotted to embrace the latter and coupled to the rocking detent. 65

6. In a motor-driven adding-machine, in combination, adding and printing mechanism, an actuating rock-shaft therefor, an electric motor, drive mechanism actuated by said motor and connected with said rock-shaft, manipulative means for operating said motor-drive, a switch for controlling the current supplied to said motor, and a device, controlled by said switch, for locking 70 said manipulative means against operative movement while said switch is at "off" position, substantially as specified. 75

7. In a motor-driven adding-machine, in combination, adding and printing mechanism, an actuating rock-shaft therefor, a 80 continuously running electric motor, drive mechanism actuated by said motor and connected with said rock-shaft, manipulative means for operating said motor-drive, a switch for controlling the current supplied to said motor, and a device, controlled by said switch, for locking 85 said manipulative means against operative movement while said switch is at "off" position, substantially as specified.

JESSE G. VINCENT.
